UNITED STATES PATENT OFFICE.

LEWIS B. BRIDGES, OF NEW YORK, N. Y. ASSIGNOR TO CORONA TYPEWRITER COMPANY, INC., OF GROTON, NEW YORK, A CORPORATION OF NEW YORK.

FOLDING TYPEWRITING MACHINE.

Application filed March 10, 1919. Serial No. 281,631.

To all whom it may concern:

Be it known that I, LEWIS B. BRIDGES, a citizen of the United States, and resident of the borough of Manhattan, city, county, and 5 State of New York, have invented certain new and useful Improvements in Folding Typewriting Machines, of which the following is a specification.

One of the objects of this invention is to 10 provide a folding typewriting machine having the appearance of a large standard machine when extended, and so constructed that the cubical dimensions thereof may be reduced approximately 50% when the machine is folded and in which the parts are 15 folded in such manner as to maintain the type basket, carriage, ribbon mechanism, escapement mechanism, and universal bar mechanism in upright positions at all times, 20 and to adapt the machine when folded to fit in an elongated rectangular case with the base of the machine resting on the bottom of the case, thus permitting the machine to be conveniently carried when folded with 25 the major portion thereof and the principal mechanisms in an upright position.

A further object of the invention is to 30 provide a typewriting machine having a main frame part supporting the type basket, and a keyboard foldable from a normal horizontal position upwardly and rearwardly to a vertical position within the forward portion of the main frame part, in such a way as to reduce the length of the machine without 35 increasing the height thereof, and having a horizontally movable frame part operable by the keyboard frame part to move the platen carriage, escapement mechanism, ribbon mechanism, and universal bar forwardly 40 horizontally from a normal rearwardly extended position to a compact position over the main frame part, the ribbon spools moving forwardly close to and in front of the lower or forward part of the keyboard and 45 overlying the higher or rear part of the keyboard, and the carriage and universal bar moving forwardly to a compact position over the type bars and in closer relation with the keyboard, thus further reducing the 50 length of the machine without increasing its height.

Another important object of the invention is to provide a typewriting machine having a foldable key action so constructed that the 55 keyboard may be folded from its normal

horizontal position to a vertical position with a portion of the keyboard forward of the type-bar rest and a portion of the keyboard below the type-bar rest, whereby the length of the machine from front to rear 60 may be reduced to a minimum when the machine is collapsed without increasing the height of the machine.

Further highly important objects of the invention are to provide a typewriting machine having a foldable type-bar action so constructed that the keyboard may be folded to a vertical position in compact relation with the type basket without increasing the height of the machine, to provide a type-bar 65 action foldable as set forth, in which positive mechanical connections are maintained at all times between the keys and the type bars, and to provide a type-bar action foldable as set forth so constructed as to obtain 70 a uniform key touch.

In the drawings Fig. 1 is a vertical sectional view of the machine in its normal extended operative position;

Fig. 2 a similar view showing the machine 80 compacted;

Fig. 3 a fragmentary vertical transverse section view;

Fig. 4 a fragmentary plan view;

Fig. 5 a detail view showing part of the 85 case shift mechanism;

Fig. 6 a detail vertical section showing the space bar mechanism;

Fig. 7 a detail side elevation showing part 90 of the case shift mechanism; and

Fig. 8 a view showing the different forms of printing key stems.

The main or relatively stationary frame part is formed with side walls 1 and a rear wall 2, the side and rear walls being cut 95 away as shown, and the front of said frame part being open. The higher parts of the side walls 1 at the front of the machine are connected by a top or finishing plate 3, and said side walls are also connected adjacent 100 their lower edges by a transverse plate or bar 4.

An upwardly and rearwardly foldable keyboard frame part 5, substantially U-shaped in plan view, is pivotally held to the 105 side walls 1 by bolts 6 which pass through the side walls 1 at points closely adjacent the bottom of the machine frame. Clamping or thumb nuts 7 are threaded on the outer ends of bolts 6 and serve when tight- 110

ened to lock the keyboard frame part 5 in either its normal horizontal position or its folded vertical position. The relatively stationary main frame part is preferably provided with rubber feet 8 at each corner thereof. The keyboard frame part is preferably provided with two rubber feet 9 at the front corners thereof, and the side walls of the keyboard frame part are preferably formed with lugs 5^a adapted to engage plate 4 when the keyboard frame part is folded, to arrest said frame part in the position shown in Fig. 2.

The printing keys 10 are arranged in three rows or banks and are supported on the upper ends of three rows of key stems 11, 12 and 13. The lower portions of the key stems of all three rows are arranged in alignment transversely of the keyboard frame part and extend vertically. The upper portion of each key stem 11 extends upwardly and rearwardly, the upper portion of each key stem 12 extends vertically and is offset slightly forwardly of the lower portion thereof, and the upper portion of each key stem 13 extends forwardly and upwardly from the lower vertically disposed portion thereof. The key stems are supported on the forward ends of two series of superposed parallel rows of levers extending fore and aft of the keyboard frame part. The levers 14 of one row are pivotally supported intermediate their ends on a common fulcrum rod or wire 15 and extend through kerfs in a bar 16 held to the keyboard frame part. The levers 17 of the lower row extend through kerfs in bar 16 and are pivotally supported on a common fulcrum wire or rod 18. The vertical portion of each key stem is connected by pivot pins 19 and 20 with the forward ends of two superposed levers 14 and 17 and the rear ends of each pair of superposed levers 14 and 17 are connected by one of a series of vertical links 21 arranged in alignment transversely of the keyboard frame part. A series of coil springs 22, held to the front cross-bar of the keyboard frame part at their forward ends and held to lugs 23 on levers 17 at their rear ends, serve to return the key stems to their normal positions after each depression of a key, the upper edges of the forward portions of levers 17 normally engaging the bottoms of the kerfs in bar 16 at the forward edge of the under side of said bar, and the upper edges of the rear portions of said levers being normally spaced from the bottoms of the kerfs, as shown in Figs. 1 and 2.

Each link 21 is formed with a rearwardly projecting lug 24 adjacent its lower end, to which the forward end of one of a series of links 25 is connected. The points of connection of all of the links 25 with lugs 24 on links 21 are in alignment transversely of the machine and coincident with the point

of fold of the keyboard frame part about the pivot bolts 6, the springs 22 serving to normally maintain said points of connection in alignment with bolts 6 or the pivotal axis of the keyboard frame part. The rear ends of links 25 are connected with the lower ends of a series of depending levers 26 pivotally held at their upper ends to a common fulcrum rod 27 which is secured at its ends to the side walls 1 of the main frame part. Each lever 26 is connected by a link 28 with one of a series of levers 29 pivotally held at their lower ends to a common fulcrum rod 30 which is secured at its ends to the side walls 1 of the stationary frame part. The levers 29 increase in length from the center toward either side of the machine, and each of said levers is connected at its upper end by a link 31 with a downwardly and rearwardly extending lug 32^a formed on its associated type-bar 32.

The type bars 32 are pivotally held at their rear ends in a type segment 33 by a common pivot wire 34, and the forward ends of said type bars are normally supported on a type rest 35 held to the type segment by a pair of rods or bars 36. The type segment is formed with end portions 37 extending through and slidable vertically in slots 38 formed in two brackets 39 which are held to the inner side of the rear wall 2 of the main frame part. The slots 38 are closed at the top and bottom to limit the up-and-down movement of the segment, and the lower edges of the end portions 37 of the segment normally rest at the bottoms of the slots and support the segment in its normal lower-case position. At the outer sides of brackets 39 the end portions 37 are formed with stub shafts 40 on each of which is mounted a roller 41.

Each type bar 32 is preferably provided with three characters, as shown, and the segment 33 is adapted to be shifted upwardly relatively different distances to middle (or cap) case position and upper (or fig.) case position. The middle-case shift key 42 is mounted on a key stem 43 similar to the key stems 13, and the upper-case shift key 44 is mounted on a key stem 45 similar to the key stems 12. The key stems 43 and 45 are each supported on the forward ends of pairs of superposed levers 14^a and 17^a similar to levers 14 and 17, said levers being fulcrumed on rods 15 and 18 and the rear ends thereof being connected by vertical links 21^a similar to the links 21. The links 21^a are formed with lugs similar to lugs 24 on links 21 to which the forward ends of two links 46 and 47 are connected at points in alignment with the points of connection of links 25 with the lugs 24. Link 47 is pivotally connected with the lower end of a rock arm 48 fixed on a rock shaft 49 which is journaled at its ends in the side walls 1 of the stationary frame

part. Link 46 is pivotally connected with the lower end of a rock arm 50 fixed to a tubular rock shaft or oscillating sleeve 51 embracing the central portion of rock shaft 49 and revoluble independently thereof. Two similarly shaped cams 52 are held to shaft 49 at opposite sides of the type segment, one cam being normally in engagement with each roller 41, and two cams 53 having a shorter throw than cams 52 are fixed on sleeve 51, one cam 53 also being normally in engagement with each roller 41. It will be obvious that when shift key 42 is depressed the segment will be moved upwardly to vary the relation between the type bars 32 and the platen 54, and that when shift key 44 is depressed the segment will be moved upwardly a greater distance than that imparted through the instrumentality of the key 42 and the cams 53 actuated thereby. A suitable spring (not shown) is provided to assist in returning the segment to its normal position.

The platen 54 is mounted on a carriage 55 traveling on a carriage bed 56. The bed 56 is rigidly held at its ends to the rear ends of a pair of forwardly extending bars 58. The bed and bars form a substantially U-shaped frame for supporting the carriage and associated devices, and said bed and bars are preferably formed integrally, the bed being formed with depending portions 57 at its ends connected with the inner faces of the bars. The ends of the carriage bed 56 are parallel with and preferably a little inside the vertical plane of the inner faces of bars 58. Bars 58 are slidably supported and guided in ways 59 which may be formed by off-setting portions of the side walls 1, as shown, or in any other suitable manner. The U-shaped frame formed by bed 56 and bars 58 is normally held in a rearwardly extended position, as shown in Figs. 1 and 4, to support the platen at the rear and above the main frame part in cooperative relation with the type bars 32, and is adapted to be locked in this position by clamping bolts 60 which extend through apertures in the side walls 3 and through elongated horizontal slots 61 in the bars 58. Suitable thumb nuts 62 are threaded on the outer ends of the clamping bolts 60.

Adjacent their forward ends bars 58 are each formed with a lateral extension or inwardly projecting bracket 63, on which brackets the spindles or shafts 64 of ribbon spools 65 are mounted. An escapement wheel 66 is journaled on a bracket 67 extending upwardly at the rear of the platen and held at its forward end to the under side of the carriage bed 56. A universal bar 68 curved to conform with the arc of the segment 33 is rigidly held to the forward ends of a pair of bars 69. The bars 69 carrying the universal bar 68 are supported to move forwardly and rearwardly by two pairs of rock arms 70 and 71 whose upper ends are rigidly held to rock shafts 70^a and 71^a journaled in suitable bearings formed on the bracket 67. The universal bar 68 is normally held in the forwardly extended position shown in Fig. 1 by means of a suitable spring, and is adapted to be engaged and moved rearwardly by the type bars 32 when the type bars are moved upwardly and rearwardly to the printing point. Suitable mechanism, such as shown in the patent to Latta, No. 1,222,550, dated April 10, 1917, may be provided for operating the carriage escapement and for feeding and vibrating the ribbon, such mechanism being mounted on the U-shaped frame part and operatively connected with the universal bar 68.

The space bar 72 is supported on the forward ends of three angle arms 73, the vertically extending rear portions 73^a of which are each pivotally held to the forward ends of a pair of superposed parallel levers 74 and 75 similar to levers 14 and 17 supporting the key stems. The levers 74 and 75 of each pair are connected at their rear ends by a vertical link 76 similar to links 21. The link 76 connecting the rear ends of the central pair of superposed levers 74 and 75 is formed with an ear or lug 77 similar to lugs 24 on links 21, and the forward end of a link 78 similar to links 25 is pivotally connected with said lug 77 in alignment with the points of connection of the forward ends of links 25 with lugs 24, and in alignment with the pivotal axis of the keyboard frame part 5. The link 78 is connected at its rear end, in the same manner as links 25 are connected with the type bars, with a blank type bar or universal-bar-operating lever 79 pivotally supported midway of the type segment 33 on the fulcrum wire 34. The free end of the blank type bar 79 normally rests on the type bar rest 35. It will be obvious that by depressing the space bar the blank type bar will be moved upwardly and rearwardly and will actuate the universal bar to letter-space the carriage without printing.

The pivoted keyboard frame part 5 is operatively connected with the U-shaped horizontally slidable frame part which supports the carriage, platen, universal bar, ribbon mechanism and escapement mechanism, to move the slidable frame along the guide-ways 59 when the keyboard frame part is shifted. The keyboard frame and the U-shaped frame are movable simultaneously toward and from each other to and from their compacted or folded positions through the medium of a pair of links 80 and a pair of levers 81. The levers 81 are pivotally held intermediate their ends to the side walls 1 of the stationary main

frame part. The upper ends of said levers have pin-and-slot connections 83 with the forward ends of the bars 58, and the lower ends of the levers are pivotally connected 5 at 84 with the rear ends of the links 80. The forward ends of links 80 are pivotally connected at 85 with the side walls of the keyboard frame part 5 at a point above the pivot point 84 and above the pivot bolt 6 10 of the keyboard frame part.

It will be obvious that the keyboard frame part may be folded upwardly and rearwardly about pivots 6 from its normal forwardly extended horizontal position to a 15 compact vertical position within the forward part of the main frame without any portion of the keyboard frame projecting above the main frame, and that when the keyboard frame is folded the bars 58 will be 20 moved horizontally forward along the ways 59 by links 80 and levers 81, thus moving the carriage, platen, universal bar, ribbon mechanism and escapement mechanism forwardly from their normal positions to more compact 25 positions over the type bars and closer to the keyboard. It will be observed also that the ribbon spools move to a compact position below the top plate 3 of the main frame and above the plane of the type basket, into 30 close relation with the lowest part of the keyboard, that the lower part of the keyboard is moved to a compact position in front of the ribbon spools and type-bar rest, while the higher part is moved to a compact 35 position below the type-bar rest, and that all of the parts mounted on the horizontally 40 slideable frame part and the upwardly swinging frame part are brought within the vertical planes of the front and rear ends of the main frame part without increasing the height of the machine when folded. The various parts of the machine are thus folded into very compact relation and in such a way that the machine when folded assumes 45 an elongated rectangular form, with the more delicate parts, such as the carriage, ribbon mechanism, escapement mechanism, universal bar and type basket, in the same planes as they occupy when in their normal 50 extended operative positions. By this arrangement the cubical dimensions of the machine may be reduced approximately 50% and the folded machine may be carried in a conveniently portable, elongated, 55 rectangular case with the base of the main frame part resting on the bottom of the case, and with the delicate mechanisms above specified in their normal planes, thus avoiding any tendency to strain or disarrange 60 parts of said mechanisms when the machine is carried in its enclosing case.

Any suitable or known means, such, for example, as integral hubs on the levers or separate spacing sleeves on the fulcrum rods, 65 may be employed for spacing the levers 26

and 29 on their fulcrum rods 27 and 30. It will be obvious also that the locking bolts 60 and slots 61 may be omitted if desired.

What I claim is:

1. In a compatible typewriting machine, 70 the combination of a relatively stationary frame part, a type segment supported thereon, a universal bar supported above the type segment, an upwardly and rearwardly movable lever fulcrumed in the type segment adapted to actuate the universal bar, a space bar, a rocking support for the space bar, a frame part on which said support is fulcrumed pivotally held to the stationary frame part to fold upwardly and rearwardly toward the universal bar, and a positive mechanical operating connection between the rear end of said rocking support and said lever foldable at a point coincident with the pivotal axis of the foldable frame 75 part.

2. In a compatible typewriting machine, 80 the combination of a relatively stationary frame part, a type segment shiftably mounted in said frame part, type bars supported 90 in said segment and movable therewith to vary the relation between the type bars and the printing point, a shift key, a rocking support for said shift key, a keyboard frame part on which said support is fulcrumed intermediate its ends pivotally held to the stationary frame part to fold upwardly and rearwardly, and an operating connection between the rear end of the rocking support and the segment for shifting the segment 95 when the key is operated, said connection being foldable at a point coincident with the pivotal axis of the keyboard frame part.

3. In a compatible typewriting machine, 100 the combination of a relatively stationary frame part, a type segment shiftably mounted in said frame part, type bars supported in said segment and movable therewith to vary the relation between the type bars and the printing point, a shift key, a rocking support for said shift key, a keyboard frame part on which said support is fulcrumed intermediate its ends pivotally held to the stationary frame part to fold upwardly and rearwardly, and a link pivotally connected with 105 the rear end of said rocking support at a point coincident with the pivotal axis of the keyboard frame part, and means connected with the rear end of said link for shifting the segment when the key is operated.

4. In a compatible typewriting machine, 110 the combination of a support, a plurality of type bars mounted thereon and normally lying in substantially horizontal planes, a 115 keyboard having a plurality of banks of keys foldable bodily from their normal operative positions to positions in which keys of the highest bank underlie the forward ends of the type bars and keys of the lowest 120

130

bank are disposed in front of the type bars, a platen carriage, means for moving the platen carriage simultaneously with the keyboard from a normal operative position above and 5 at the rear of the rear ends of the type bars to a compact position in the same horizontal plane close to the lowest bank of keys of the folded keyboard and overlying the type bars, a pair of ribbon spools supported in front 10 of the carriage to move therewith into close relation with the forward part of the keyboard when the machine is compacted, and a universal bar movable with the carriage into and out of cooperative relation with the 15 type bars.

5. In a compactible typewriting machine, the combination of a platen, type bars, and foldable key-operated means for varying the relation between the platen and type bars 20 for printing different case characters, said means embodying a support foldable upwardly and rearwardly toward the platen and type bars, a shift key foldable with said support, a rocking device fulcrumed 25 intermediate its ends on said support and carrying said key at its forward end, a link pivotally connected with the rear end of said device at a point coincident with the point of fold of said support, and means 30 connected with the rear end of said link for imparting a relative movement between the platen and type bars when the key is depressed.

6. In a compactible typewriting machine, 35 the combination of a frame having a relatively stationary intermediate portion upon which certain of the working parts are mounted and portions movable relatively to said intermediate portion upon which 40 other working parts are mounted, and connections between said frame portions whereby the movable portions may be shifted to move the working parts mounted thereon from normal positions respectively fore and 45 aft of the intermediate portion to compact inoperative positions within the vertical planes of the edges of the intermediate portion without increasing the height of the machine, the working parts on one of said 50 movable portions being bodily shiftable therewith out of cooperative relation with cooperating parts on the stationary portion and the working parts on the other movable portion having foldable constantly maintained operating connections with working 55 parts on the stationary portion.

7. In a compactible typewriting machine, 60 the combination of a stationary frame part, a keyboard having printing keys and shift and spacing keys, a platen, platen feeding 65 and ribbon carrying means and a universal bar associated with the platen, type carriers mounted on the stationary frame part operatively connected with the printing keys and adapted to actuate the universal bar,

means for varying the relation between the type carriers and platen mounted on the stationary frame part and operatively connected with the shift keys, means mounted on the stationary frame part and operatively 70 connected with the spacing key for actuating the universal bar, and means whereby the platen and its associated devices may be shifted bodily forward in unison while upright and the keys of the keyboard shifted 75 upwardly and rearwardly in unison to place the keys and the platen and its associated devices within the vertical planes of the edges of the stationary frame part.

8. In a compactible visible typewriting 80 machine, the combination of a main frame part, a keyboard frame part pivotally connected at its rear end to the forward end of the main part, a plurality of key-operated levers fulcrumed on the key board frame 85 part, type bars extending fore and aft of the machine operable by the key-operated levers mounted on the main frame part with their forward ends at the rear of the key-operated levers, a frame part slidably held 90 to the main frame part to move forwardly and rearwardly, a platen carriage mounted on the slidable frame part and normally overhanging the rear end of the main frame part, and connections between the keyboard 95 frame part and slidable frame part whereby the same may be simultaneously shifted to place the keyboard frame part and also the key-operated levers in their entirety in compact vertical positions close to the forward ends of the type-bars and to place the platen carriage in a compact upright position overlying the type-bars.

9. In a compactible typewriting machine, 105 the combination of a main frame part, type-bars mounted in the main frame part and normally extending substantially fore and aft of said frame part, a keyboard frame part pivotally held to the main frame part to fold upwardly and rearwardly to an 110 edge-wise position within the forward end of the main frame part, key-operated devices mounted on the keyboard frame part, constantly maintained foldable operating connections between the key-operated de- 115 vices and type bars, a platen support normally overhanging the rear end of the main frame part, and connections between the platen support and keyboard frame part for shifting the platen support to a compact po- 120 sition overlying the type-bars when the keyboard frame part is swung to its compacted position.

10. In a compactible typewriting machine, 125 the combination of a main frame part, type bars mounted in the main frame part, a frame part slidably held to the main frame part to move forwardly and rearwardly, a platen carriage mounted on the slidable frame part and normally overhanging the 130

rear end of the main frame part, a pair of ribbon spools mounted on the slideable frame part in front of the carriage, a key-board frame part pivotally held to the main frame 5 part to fold upwardly and rearwardly to a vertical position in front of the type-bars, stepped rows of keys operatively connected with the type bars foldable with the key-board frame part into edgewise positions 10 close to the type-bars, and means operable by the upward and rearward movement of the pivoted keyboard frame part for moving the slideable frame part forwardly to place the ribbon spools close to the upper 15 end of the folded keyboard and above the rear rows of keys and place the platen carriage above the type-bars.

11. In a compactible front-strike type-writing machine, the combination of a support, a plurality of type-bars mounted on 20 the support, a keyboard arranged in substantially the same horizontal plane with said type-bars having stepped transverse rows of keys for operating the type-bars 25 foldable to edgewise positions in which keys of the highest row underlie the forward ends of the type bars and keys of the lowest row are disposed in front of the type-bars, a platen carriage, and means whereby the 30 platen carriage may be moved from a normal position beyond the rear end of the support to a compact position overlying the type bars and closer to the lowest row of keys of the keyboard.

35 12. In a compactible front-strike type-writing machine, the combination of a support, a plurality of type-bars mounted on the support, a keyboard arranged in substantially the same horizontal plane with said 40 type-bars having stepped transverse rows of keys for operating the type-bars foldable to edgewise positions in which keys of the highest row underlie the forward ends of the type bars and keys of the lowest row are 45 disposed in front of the type-bars, a platen carriage, and means operable by folding the keyboard for moving the carriage forwardly while upright from a normal rearwardly extended position to a more compact position 50 over the type-bars.

55 13. In a compactible typewriting machine, the combination of a main frame part, printing instrumentalities mounted in the main frame part, a keyboard frame part pivotally held at its rear end to the forward end of the main frame part adjacent the base of the main frame part to swing upwardly and rearwardly to a vertical position, a plurality of key-operated devices supporting stepped 60 banks of keys mounted on the key-board frame part and foldable therewith in their entirety to place the banks of keys in edgewise positions within the main frame part with certain of the keys under the 65 printing instrumentalities and others in

front of the printing instrumentalities, a platen carriage normally overhanging the rear end of the main frame part, a support for the carriage slideably held to the main frame part, and means operable by the keyboard frame part for sliding the carriage support forwardly when the keyboard frame part is swung upwardly. 70

14. In a compactible front-strike type-writing machine, the combination of a main frame part, type bars mounted on the main frame part, a foldable keyboard frame part hinged to the forward end of the main frame part, key-operated levers fulcrumed on the keyboard frame part operatively connected 75 with the type-bars, a platen carriage, a shiftable support for the platen carriage normally supporting the platen carriage at the rear of the main frame part, a universal bar operable by the type bars and mounted on 80 the carriage support, and connections between the keyboard frame part and carriage support for moving the platen carriage and universal bar to compact positions over the type-bars when the keyboard frame part is 85 folded upwardly and rearwardly.

15. In a compactible front-strike type-writing machine, the combination of type-bars, a platen carriage normally supported at the rear of the type-bars, a keyboard normally supported forwardly of the type-bars and in substantially the same horizontal plane therewith, means whereby the keyboard may be folded upwardly and rearwardly to a compact vertical position in 100 close relation with the forward ends of the type-bars, and means controlled by the folding movement of the keyboard for moving the carriage to a compact position over the type-bars. 105

16. In a compactible front-strike type-writing machine, the combination of type-bars, a platen carriage normally supported at the rear of the type-bars, a keyboard normally supported forwardly of the type-bars 110 and in substantially the same horizontal plane therewith, means whereby the keyboard may be folded upwardly and rearwardly to a compact vertical position in close relation with the forward ends of the type-bars, and means controlled by the folding movement of the keyboard for moving the carriage to a compact position over the type-bars, means for limiting the folding movement of the keyboard, and means for 115 locking the keyboard and carriage in both their compacted and extended operative positions. 120

17. In a compactible typewriting machine, the combination of a main frame part, type bars mounted on the main frame part and normally extending substantially fore and aft thereof, key-operated levers supporting keys arranged in transverse rows at different heights, and a keyboard frame part in which 125 130

the key-operated levers are fulcrumed hinged at its rear end to the forward end of the main frame part at a point adjacent the base of the main frame part and foldable 5 to a vertical position in which certain of the keys are located below the type-bars and others in front of the type bars.

18. In a compactible typewriting machine, the combination of type-bars, key-operated 10 levers for operating the type bars normally extending fore and aft of the machine and located wholly forward of the type-bars, a

platen normally located above and at the rear of the type-bars, and means whereby the key-operated levers and platen may be 15 shifted relatively to the type-bars to compact inoperative positions in which the key-operated levers are arranged in their entirety on end in front of the type-bars and the platen is arranged over the type-bars. 20

This specification signed this fifth day of March, A. D. 1919.

LEWIS B. BRIDGES.
